Specification of Letters Patent.

Patented Nov. 2, 1915.

Application filed July 24, 1912. Serial No. 711,323.

To all whom it may concern:

Be it known that we, EDWARD M. LANG, Jr., a citizen of the United States, residing at Portland, county of Cumberland, State of Maine, and CHARLES W. SLEEPER, a subject of His Majesty the King of Great Britain, and resident of Lancaster, county of Coos, State of New Hampshire, have invented certain new and useful Improvements in Cap-
10 Droppers, of which the following is a specification.

This invention relates to feeding devices, and particularly to the dropping and delivering of can caps and articles of a like nature. As the machine which forms the embodiment of the invention is especially adapted to drop can caps and place them on the filling opening of a can the invention will be discussed with particular reference
15 to that art. It will be, however, understood that the mechanisms involved herein are capable of various uses and applications.

The feeding and placing of can caps involves many difficulties due to the liability
20 of jamming or mutilating the caps, and to the necessity of delivering a cap to each can so accurately that it will exactly overlie the filling opening. This has been particularly difficult in view of the variety of sizes of
25 cans employed and in the difference of the spacing of the cans on the conveyer. It has been found of great advantage to drive the so-called dropper from the cans themselves as they pass on the conveyer. This varying
30 distance between the cans makes it difficult to secure uniform and accurate dropping under all circumstances. The present invention, therefore, combines a driving mechanism operated by the cans themselves with a
35 dropping and placing mechanism of such construction and in such relation that it may be operated by cans at any distance of spacing.

The object of the invention is, further,
40 directed to overcoming the liability of the machine to jam on any misplaced or bulged cans which may be on the conveyer. To overcome this difficulty the invention includes certain improvements in the mounting of the device to permit the yielding of
45 the machine relative to the carrier. The jamming of the caps within the dropping mechanism is also avoided by the introduc-

tion of yielding elements in the driving and guiding of those parts which engage the cap. 55

The construction and operation of this machine will be more fully set forth in the specification which follows.

Throughout specification and drawings like reference numerals are employed to indicate corresponding parts and in the drawings:—

Figure 1 is a plan view of the dropping device, the delivery chute being partly broken away, Fig. 2 is a rear elevation 65 partly in section of the machine, Fig. 3 is a detail partly in section of the locking mechanism, Fig. 4 is a side sectional view on the line 4—4, Fig. 1, also showing part of the can feed of the endless chain type, Fig. 5 is 70 a sectional view of the cap chute, picking and dropping slide and delivery slide together with their mountings on the line 5—5 of Fig. 1, Fig. 6 is a plan view of the same with the guides removed, Fig. 7 is a section 75 on the line 7—7, Fig. 6, Figs. 8 and 9 are details of the cap separating and dropping mechanism, Fig. 10 is a further view corresponding to Fig. 6 but showing the cam slide at the other end of its throw, Fig. 11 80 is a section of the slides on the line 11—11, Fig. 6, Fig. 12 is a detail of the cap slide operating mechanism, Fig. 13 is a view of the driving mechanism partly in section with the position of the cans indicated in 85 dotted lines, and Fig. 14 is a detail of the yielding pivotal support and the supporting bearings of the dropping mechanism.

The machine, as illustrated in the drawings, is adapted to be used in connection 90 with any form of can conveyer, as for instance the endless chain type, of which we have illustrated a cross section in connection with the showing in Fig. 4, in which the lateral guides of the conveyer are indicated 95 at 1 with the conveyer chain 2 running between them, having upwardly projecting dogs 3 adapted to engage a cam and carry it forward to the machine.

The feeding and dropping mechanism is 100 mounted on a bearing 5 pivoted at 5^a to a clamp 9 suitably held to the bed of the conveyer by a bolt 9¹ and having a depending flange 9² between which and the lower portion of the bearing 5 is interposed a spring 8. 105 In the bearing 5 is mounted a vertical sup-

porting rod held against rotation therein by a set screw 4¹.

The rod 4 is supported on the bearing 5 by a sleeve 6 set by a screw 6¹. Clamped to the rod 4 and in a proper position relative to the conveyer 2 is a supporting collar 50 clamped by a bolt 51 and supporting a ball race 52. Above this race is rotatably supported a hollow shaft 13 which surrounds the rod 4 and about the hollow shaft 13 is a sleeve 12¹ upon which a hub 18 is fixed. Loosely surrounding the sleeve 12¹ and below the hub 18 is a notched disk 15 adjustable with relation to the hub 18 by means of a pair of tangential screws 19, one of which is threaded through a post set in the disk 15 and the other through a post set in the hub 18. This affords the slight circumferential adjustment required in timing the dropping of the caps.

The notched disk 15 is yieldingly held in fixed relation to the plate 10 by a latch 16 having a pointed end adapted to enter the notches 15¹ of the disk. The latch may be moved out by the lever 16¹ which has a cam shoulder which bears against the block 10¹ formed on the plate 10 and through which the latch 16 passes. The latch is yieldingly held in its disk engaging position by a spring pressed locking plunger 16³. This plunger 16³ has a beveled end which permits the latch 16 to yield in case there is any jamming of the caps or obstruction to the drive.

The machine is driven by the cans C as they pass by on the conveyer. Pivoted to the plate 10 at equal distances from its axis of rotation are a plurality of can engaging arms 11. These arms are each pivoted between their own ends and the rear end of each arm is in turn pivoted to an annular ring 12 rotatably supported on flanged rollers 13¹ carried by the ends of the rods 7 adjustably held by set screws 7¹ in the bearing 5 as shown in Fig. 2.

At the upper end of the hollow shaft 13 is mounted a pinion 20 which meshes with a pinion 21 to drive a pinion 22 set on the shaft 22¹ which carries a crank arm 24 surrounded by a roller 25. The roller 25 works in a cross slot 26 of a cam slide 27 having cam slots 27¹.

At the upper end of the supporting rod 4 is mounted a casting 60 including a suitable casing for the gears 20 and 21, and having a lateral overhang 62 provided with a bottom 43 forming a channel within which overhanging guides 64 and 65 are adjustably supported for centering the cap with relation to the can as indicated by dotted lines at C in Fig. 4. The shanks of the guides 64 and 65 are slotted and held to the frame 62 by set screws 66. Bolted to the casing extension 62 is the delivery chute 70 having a V-shaped channel 71¹ on its upper face

and a shallow groove 72 on its lower side. Within the groove 72 is set an adjustable strip 73 adjustably held by a clamping screw 74 by which its forward end 73¹ may be properly positioned for supporting the adjacent edge of the bottom caps P.

The extension 62 of the casing casting carries a further extension 67 in which are formed an upper and lower set of slide-ways. In the lower slideway is a pusher 75 slide 80 working on the plate 43 which forms a supporting shelf on which the caps P are dropped after they are separated from the column in which they are fed down the chute 70.

The chute 70 is V-shaped and is set at an incline of about 45% so that the circular caps rest thereon in substantially vertical position. At the lower end, however, the chute is downwardly curved, causing the caps to pass from a vertical to a more horizontal position. This causes an opening of the column on its outer edge and a slight separation of the outer edges of the individual caps which permits them to be more readily separated by the slide 28.

The placing slide 80 is operated by a lever 81 pivoted at 82 in the brackets 83 and operated by a roller 84 on a crank 85 formed on the shaft 22¹. The lever 81 is slotted to receive the roller 84 and at its free end is again slotted at 86 to receive a roller 87 on a stud 88 set on the slide 80.

Above the slideway 80 is formed in the casting a slideway 90 in which a pair of 100 carrier slides 33 and 34 work. The carrier slide shown in Fig. 7 is held at the lower end of said slot by a spring 37 backed by a screw 37¹. The stud 38 carries a picker blade 28 which is clamped to it by a screw 38¹ and a suitable washer 38². The other slide 33 has clamped to it a dropper blade 29 held by a screw 33¹ and washers 33². The slide 34 has a stud 32 and the slide 33 a stud 31, both of which project through a 110 cam slot 27¹ on the cross slide 27. The picker and dropper blades 28 and 29 are each cut away to clear the studs 32 and 31 as appears in Fig. 10.

The cam slide 27 works in a slideway 100 115 cut on the lower faces of a block 101 attached to that part of the extension 67 in which the slideways 90 are formed by screws 102. The upper face of the block 101 is channeled at 103 and in this channel a narrow plate 104 is adjustably held by a screw 106 passing through a slot 107 therein.

On the lower end of the plate 104 there is removably mounted a vertically disposed guide block 108 which is set opposite to the 125 lower end of the chute 70. The chute 70 supports one edge of the caps and the plate 104 supports the opposite edge of the caps P as they reach the lower end of the V-shaped chute 70. This adjustability of the 130

block 108 relative to the V-shaped chute permits a wide scope of use of the machine for caps of different sizes.

Just in the rear of the block 108 a tubular casing 109 is tapped through the plate 104. In the lower end of this casing is a ball 110 bearing against the upper face of the picker blade 28. The ball 110 is yieldingly held against the blade by a spring 111 backed by a screw plug 112 so that the pressure on the picker blade 28 may be adjusted as desired. In this manner the picker blade is yieldingly held down against the dropper blade 29 but permitted to yield upwardly 15 to ride over the edge of the bottom cap P^1 when necessary in penetrating between the bottom cap P^1 and the cap P^2 which lies next above it.

The transverse movement of the cam slide 27 imparts to the slides 33 and 34 a longitudinal reciprocation in their slideways and a corresponding movement of the picker blade 28 and the dropper blade 29 for the purpose of separating and dropping a cap 25 from the column. In this operation, as indicated in Figs. 5, 8 and 9, the column normally lies in the position shown in Fig. 5. One edge of the column of caps is supported against the projecting edge 73¹ of the strip 30 73 and the other edge of the column rests against the block 108 and overlying and resting upon the end of the dropper slide 29 at the rear of its recessed point 29¹.

Upon the first movement of the machine 35 to drop a cap, the picker slide 28 advances and thrusts its forward edge between the bottom cap and the cap lying next above it. In this movement it may yield upwardly if necessary against its spring 111. The dropper blade 29 is slightly withdrawn by a simultaneous movement so that the bottom cap P^1 falls into the recess 29¹ at the forward end of the dropper slide 29 at the same moment the picker slide 28 starts to 40 insert itself between the caps. In this way the certainty of separation is secured and the danger of mutilating the caps is avoided. As soon as the picker slide has advanced 45 sufficiently to support the cap P^2 and the superimposed column of caps, the dropper blade 29 recedes slightly, permitting the adjacent edge of the lower cap P^1 to fall into the recess 29¹ formed at its point, as is shown in Fig. 8. The caps P are slightly 50 dished and are fed in inverted position. This dropping of the adjacent edge of the lower cap P into the recess 29¹ causes the cap P to be supported in a tilted position in 55 relation to the cap next above it. During 60 this time the picker blade 28 is traveling forward and rides on the upper surface of the cap supported by the dropper blade 29. As the slide 28 approaches the end of its advance the dropper blade 29 is receding, 65 causing a tilt at the opposite side of the cap

P^2 against the point 73¹ on which it is supported. The bottom cap is thus wholly separated from that next above it, but is still being pressed down by the point of the picker blade 28 against the point 29² of the dropper 70 29. As the dropper 29 continues to recede and the picker 28 to advance, the cap P is worked off from the point 29² and dropped with a sharp release which allows it to fall in a horizontal position on to the 75 shelf 43 from which it is pushed by the pusher slide 80.

The pusher slide 80 slips the cap from the shelf 43 on to the open top of the can just below it as presented by the conveyor 2. 80 It is of course essential that this delivery of the cap to the can be timed with great exactitude so that the cap will be lodged in proper position on the can in registry with its filling opening. This adjustment is secured through the tangent screws 19 which 85 relatively adjust the transmitting mechanism between the disk 10 and the gearing 20, 21, etc. of the dropping mechanism.

The eccentricity of the ring 12 is adjusted 90 by the positioning of the rods 7 which may be rotated and clamped by a set screw 7¹ to adjust their eccentric ends 7² so that the ring 12 may be set laterally in either direction by changing the position of these ends 95 7² on which the flanged rollers 13¹ turn.

The machine having been adjusted for proper height by the supporting collars 6 and properly timed by the tangent screws 19 for accurate dropping and placing, and the 100 guides 64 and 65 and the block 108 having been properly adjusted for the desired diameter of cap, the chute 70 is filled with caps placed concave side down. The machine is started from the position shown in 105 Fig. 5 in which position one side of the bottom cap is supported on the point 73¹ and the other side supported just back of the recess 29¹ of the dropper 29. As the machine is actuated by each can as it passes, 110 one cap should be placed on the shelf 43 so that as the first can passes, the cap will be delivered to it. The first can in passing engages one of the arms 11 and rotates the disk 10 one sixth of a revolution. Each full 115 revolution of the disk causes six complete cycles of the dropping mechanism.

It will be noted that the pressure of each can when engaging with the outer end of the arm 11 is transmitted to the ring 12. 120 The ring 12 is held against any lateral motion under this tendency by the roller 13¹ on the right of Fig. 2.

The machine is guarded against damage from jamming by the yielding mounting of 125 the bearing 5. Referring to Fig. 4 it will be seen that if the can C should be slightly tilted by having one edge rest on the top of one of the dogs 3 or if the can should have its top bulged on account of a lateral dent 130

in the side as sometimes happens, the pressure against the plate 43 will cause the entire dropping device to rock slightly on the pivot 5^a, permitting the can to pass without breaking the casting.

5 The jamming of caps is prevented by the yielding mounting of the picker blade 28. In case a cap becomes tilted in vertical position, instead of horizontal position, as indicated in Fig. 5, or stands on edge on the 10 plate 43 the slide is permitted to yield against the spring 37 which is adjusted under a light tension. The upward yielding of the picker blade, in addition to its normal yielding functions for the purposes of 15 separation of the caps, introduces a further element of safety in that by so doing it avoids the possibility of its jamming any of the caps P. In this connection it must 20 be borne in mind that the caps P are of thin stock and are very easily bent, and that even a slight bending, such as would be hardly perceptible to the eye, will prevent the proper fitting of the cap and the uniting of 25 the parts by the solder.

The caps, as illustrated, are the so-called hemmed cap having a binding of solder p about the margins which is fused to solder the cap over the open mouth of the can.

30 While the several elements of the machine, as shown and described, do combine for great efficiency and accuracy of result, and while certain of the parts are dependent on each other, nevertheless various modifications in 35 the form and arrangement of the parts may be had, and the machine and parts thereof may be variously adapted for different work, all without departing from the spirit of our invention if within the limits of the 40 appended claims.

What we, therefore, claim and desire to secure by Letters Patent is:—

1. In a machine of the class described, a support for a plurality of can caps, a dropping mechanism for dropping the caps one by one, a placing mechanism for placing a dropped cap on a can top, a can engaged drive operatively connected with said dropping and placing mechanism and comprising 45 a rotatable member, a plurality of can engaged arms pivoted between their ends at equal distances from the center of rotation of said rotatable member, a second rotatable member supported for rotation about an axis eccentric to said first named member, one end of each of said arms being pivoted thereto at equal distances from said eccentric axis.

60 2. In a machine of the class described, a cap placing mechanism for placing can caps on the open end of a can, a can engaged drive operatively connected with said placing mechanism and comprising a rotatable member, a plurality of can engaged arms 65 pivoted between their ends at equal distances

from the center of rotation of said rotatable member, a second rotatable member supported for rotation about an axis eccentric to said first named member, one end of each of said arms being pivoted thereto at 70 equal distances from said eccentric axis.

3. In a machine of the class described, a support for a plurality of can caps, a dropping mechanism for dropping the caps one by one, a placing mechanism for placing a dropped cap on a can top, a can engaged drive operatively connected with said dropping and placing mechanism and comprising a rotatably supported driving disk, a plurality of can engaged arms pivoted between 75 their ends at equal distances about said disk, a ring, means for suitably supporting said ring about an axis eccentric to said disk, one end of each of said arms being pivoted to said ring.

4. In a machine of the class described, a support for a plurality of can caps, a dropping mechanism mounted adjacent to said support for dropping the can caps one by one, a can engaging drive operatively connected with said dropping mechanism and comprising a rotatably supported driving disk, a plurality of can engaging devices pivoted between their ends at equal distances about said disk, a ring, and means 90 for suitably supporting said ring about an axis eccentric to said disk, one end of each of said engaging devices being pivoted thereto.

5. A machine for feeding articles of the class described, comprising a chute for supporting a plurality of superimposed articles, an inclined shoulder on one side of said chute adapted to support the bottom article, a pair of reciprocating members oppositely 105 disposed to said shoulder, comprising a superimposed vertically yielding penetrating member and underlying dropping means having supporting surfaces in two different horizontal planes, one for initially supporting the adjacent edge of the bottom article and the other for supporting the said adjacent edge of said lower article subsequent to penetration and means for moving said penetrator and dropper to release said article.

6. A machine for feeding articles of the class described, comprising a chute for supporting a plurality of superimposed articles, an inclined shoulder on one side of said chute adapted to support the bottom article, a pair of reciprocating members oppositely disposed to said shoulder, comprising a superimposed vertically yielding penetrating member and underlying dropping means having supporting surfaces in two different horizontal planes, one for initially supporting the adjacent edge of the bottom article and the other for supporting the said adjacent edge of said lower article subsequent 120 125 130 135

to penetration with its upper surface in frictional contact with said penetrator and means for moving said penetrator and dropper to release said article.

5 7. A machine for feeding articles of the class described comprising a chute for supporting a plurality of superimposed articles, means on one side of said chute adapted to support the bottom article, a pair of 10 reciprocating members oppositely disposed to said supporting means, comprising a superimposed penetrating member and underlying dropping means, and means for yieldingly moving said penetrator and for positively moving said dropper to release said article.

8. A machine for feeding articles of the class described, comprising a chute for supporting a plurality of superimposed articles, 20 means on one side of said chute adapted to support the bottom article, a pair of reciprocating members oppositely disposed to said supporting means, comprising a superimposed vertically yielding penetrating member 25 and underlying dropping means, and means for yieldingly moving said penetrator and for positively moving said dropper to release said article.

9. A machine of the class described comprising a support, a bearing pivotally mounted thereon, a rotatable member mounted on said bearing, can engaging means associated with said member for the rotation thereof, a frame supported on said rotatable 30 member, a gravity chute on said frame for supporting a column of caps, a pair of slides mounted adjacent to the bottom of said chute, a transverse cam slide having a suitable cam slot therein, studs on said slides 35 and entering said slot, means for reciprocating said cam slide from said rotatable member for operating said slides to drop a cap, and a pusher mounted below said slides and 40 adapted to deliver the dropped cap, and operated by the means for reciprocating said cam slide.

10. A machine of the class described, comprising a support, a bearing pivotally mounted thereon, a resilient means for maintaining said bearing in vertical position, a rotatable member mounted on said bearing, can engaging means associated with said member for the rotation thereof, a frame supported on said rotatable member, a gravity chute on said frame for supporting a column of caps, a pair of slides mounted adjacent to the bottom of said chute, a transverse cam slide having a suitable cam slot 50 therein, studs on said slides and entering said slot, means for reciprocating said cam slide from said rotatable member for operating said slides to drop a cap, and a pusher mounted below said slides and adapted to deliver the dropped cap, and operated by the 55 means for reciprocating said cam slide.

60

11. A machine of the class described, comprising a support, a bearing pivotally mounted thereon, a rotatable member mounted on said bearing, can engaging means pivotally associated with said member for the rotation thereof, 70 a frame supported on said rotatable member, a gravity chute on said frame for supporting a column of caps, a pair of slides mounted adjacent to the bottom of said chute, a transverse cam slide having a suitable cam slot therein, studs on said slides and entering said slot, a vertically and longitudinally yielding penetrating blade on one slide and a dropper blade on the other slide, means for reciprocating 75 said cam slide from said rotatable member for operating said blades to separate and drop a cap, and a pusher mounted below said slides and adapted to deliver the dropped cap, and operated by the means for reciprocating said cam slide.

80

12. A machine of the class described, comprising a support, a bearing pivotally mounted thereon, a resilient means for maintaining said bearing in vertical position, a rotatable member mounted on said bearing, can engaging means pivotally associated with said member for the rotation thereof, 85 a frame supported on said rotatable member, a gravity chute on said frame for supporting a column of caps, a pair of slides mounted adjacent to the bottom of said chute, a transverse cam slide having a suitable cam slot therein, studs on said slides and entering said slot, a vertically and longitudinally yielding penetrating blade on one slide and a dropper blade on the other slide, means for reciprocating said cam slide from said rotatable member for operating 90 said blades to separate and drop a cap, and a pusher mounted below said slides and adapted to deliver the dropped cap, and operated by the means for reciprocating said cam slide.

95

13. In a machine of the class described, a conveyer for successively presenting a plurality of open top containers, means adjacent to the part of the container tops for supporting a plurality of covers, means for delivering said covers successively to said 100 open container tops in passing, a mounting for cover supporting means for positioning the same adjacent to said path of the container tops including a laterally yielding connection effective upon contact of a container top with said supporting means.

110

14. A machine of the class described, comprising a feeder and a conveyer for presenting a series of articles to said feeder, a drive for said feeder, comprising a rotatable member, a plurality of successively protrudable article engaging arms pivoted between their ends at equal distances from the center of rotation of said rotatable member, a second rotatable member supported about an axis 115

120

125

130

6 eccentric to said first named member, one end of each of said engaging arms being pivoted thereto at equal distances from said eccentric axis and the other end being adapted to be disposed across said conveyer when in protruded position.

15. A machine of the class described, comprising a feeder and a conveyer for presenting a series of articles to said feeder, a drive 10 for said feeder comprising a rotatable member, a plurality of successively protrudable article engaging arms pivoted between their ends at equal distances from the center of rotation of said rotatable member, a ring 15 supported for rotation about an axis eccentric to said first named member, one end of each of said engaging arms being pivoted to said ring at equal distances thereon and the other end being adapted to be disposed 20 across said conveyer when in protruded position.

16. A machine of the class described, comprising a feeder and a conveyer for presenting a series of articles to said feeder, a drive 25 for said feeder comprising a driving shaft operatively connected with said feeder, a disk mounted on said shaft, a plurality of engaging arms pivoted between their ends at equal distances about said disk, a ring, means 30 for rotatably supporting said ring about an axis eccentric to said shaft, one end of each of said engaging arms being pivoted to said ring at equal distances thereon and the other end being adapted to be disposed 35 across said conveyer when in protruded position.

17. In a machine of the class described, a chute for supporting a plurality of superimposed articles, a slide operating in the 40 plane of the lower surface of the bottom article, a slide operating in the plane of the top surface of the bottom article, means for yieldingly pressing down on said upper slide, and means for reciprocating both of 45 said slides.

18. In a machine of the class described, a chute for supporting a plurality of superimposed articles, a slide operating in the plane of the lower surface of the bottom 50 article, a slide operating in the plane of the top surface of the bottom article, means for yieldingly pressing down on said upper slide, and means for reciprocating both of said slides, including a yielding stud engaging 55 said upper slide.

19. In a machine of the class described, a chute for supporting a plurality of superimposed articles, a slide operating in the plane of the lower surface of the bottom 60 article, a slide operating in the plane of the top surface of the bottom article, and means for reciprocating both of said slides, including a yielding stud engaging said upper slide.

65. 20. In a machine of the class described, a

chute for supporting a column of superimposed articles, a support for the bottom article at one side of said chute, a pair of superimposed reciprocating members disposed at the other side of said chute and comprising an upper vertically yielding penetrator and a lower dropper having a recessed point, reciprocating mechanism having successive phases of operation effective to advance the point of said dropper beyond the column 70 edge to support the adjacent side of the bottom article behind said recess to advance said penetrator to ride over the upper edge of said article, to withdraw said dropper to permit the adjacent edge of the article to 75 fall within said recess, to further retract said dropper to lower the opposite side of said bottom article and to completely withdraw the forward end of the dropper to 80 wholly release the article.

85. 21. In a machine of the class described, a chute for supporting in column a plurality of superimposed articles, a support for the bottom article at one side of said chute, a pair of superimposed reciprocating members 90 disposed at the other side of said chute and comprising an upper penetrator and a lower dropper having a recessed point, a yielding element against which the upper face of said penetrator finds bearing, reciprocating 95 mechanism having successive phases of operation effective to advance the point of said dropper beyond the column edge, to support the adjacent side of the bottom article behind said recess, to advance said 100 penetrator to ride over the upper edge of the article, to withdraw said dropper point to permit the adjacent edge of the article to fall within said recess, to further retract said dropper to lower the opposite side of 105 said bottom article, and to completely withdraw the forward end of the dropper wholly releasing the article.

110. 22. In a machine of the class described, a chute for a column of superimposed articles to be fed, a support for the bottom article of said column, a penetrator having its separating edge alined for entrance between the bottom article and the one next above it, means to advance the penetrator to 115 separating position means effective to initially lower one side of the bottom article, then to lower the opposite side thereof and finally to wholly release the article thus separated.

120. 23. In a machine of the class described a chute for a column of superimposed articles to be fed, a support for the bottom article of said column, a penetrator having its separating edge alined for entrance between said 125 bottom article and the one next above, means to advance the penetrator to separating position and means simultaneously effective to initially lower one side of the bottom article, to lower then the opposite side thereof 130

after penetration, and finally to wholly release the article thus separated.

24. In a machine of the class described, a gravity chute for a column of superimposed articles to be fed, a support for the bottom article of said column, means for temporarily separating the article next above the bottom article, and means effective to initially lower one side of the bottom article, 10 said last named means co-acting with the separating means to then lower the opposite side thereof, and finally to wholly release the article thus separated.

25. In a machine of the class described, a chute for a column of superimposed articles to be fed, a support for one side of the bottom article, a pair of members opposite said support and transversely movable relative thereto, means for yieldingly holding said 20 members in contact with each other, means for moving said members to engage on upper and lower sides of the bottom article, and then to withdraw the lower member to wholly release the same.

25. 26. In a machine of the class described, a gravity chute for a column of superimposed articles to be fed, a support for the bottom article of said column, means for temporarily separating the same and the article 30 next above the bottom article, said support including means effective to lower the side of the bottom article farthest from the chute, said last named means co-acting with the separating means to then lower the opposite side of said article nearest to said chute, and finally to wholly release the article thus separated.

27. In a machine of the class described, an inclined V-shaped gravity chute adapted to 40 support one edge of each of a plurality of articles to be fed and an adjustably mounted block set opposite to the lower end of said chute to support the opposite edge of said articles in their passing.

45. 28. In a machine of the class described, a V-shaped conductor for a column of flat articles to be fed having a cured portion therein, and a penetrator radially disposed to

said curved portion on the curved side thereof, and means for moving said penetrator 50 to cause it to enter between the edges of said articles in rounding said portion.

29. In a machine of the class described, a chute for supporting a plurality of superimposed articles, a member operating 55 in a direction transverse to the direction of feed of said articles and normally disposed in supporting relation to the bottom article, a member disposed for penetrative advancement between the bottom article 60 and the article next above whereby to temporarily support said article next above, a guide element in association with said penetrator member permitting yielding movement of said member in a direction trans- 65 versely to its line of movement, whenever necessary, whereby to prevent jamming of said articles, and means for imparting operative movement to said members.

30. In a machine of the class described, a 70 chute for supporting a plurality of superimposed articles, a member operating in a direction transverse to the direction of feed of said articles and normally disposed in supporting relation to the bottom article, a 75 member operating in the line of movement of the first named member and disposed for penetrative advancement between the bottom article and the article next above whereby to temporarily support said article next 80 above, an adjustable guide element in association with said penetrator member permitting yielding movement of said member in a direction transversely to its line of movement whenever necessary whereby to 85 prevent jamming of said articles, and means for imparting operative movement to said members.

In testimony whereof we affix our signatures in the presence of two witnesses.

EDWARD M. LANG, JR.
CHARLES W. SLEEPER.
